(57) **ABSTRACT**

A new and distinct cultivar of flowering dogwood tree, which has fused bracts is provided. This dogwood tree is botanically known as *Cornus kousa* and referred to by the following cultivar name: 'Pam's Mountain Bouquet'.

3 Drawing Sheets

1

BACKGROUND OF THE INVENTION

The present invention relates to a new and distinct cultivar of flowering dogwood tree cultivar, which has fused bracts. This dogwood tree is botanically known as *Cornus kousa* and hereinafter referred to by the following cultivar name: 'Pam's Mountain Bouquet'.

This new dogwood cultivar was discovered in a planting of seedlings within a cultivated area in Oak Ridge, Tenn. 'Pam's Mountain Bouquet' is a selection from the original seedlings grown in Oak Ridge, Tenn. from seed gifted by Polly Hill. Asexual reproduction of 'Pam's Mountain Bouquet' by rooting of harvested terminal cuttings and grafting of axillary buds onto seedling rootstocks in Oak Ridge, Tenn. and at a nursery located in Belvidere Tenn. have shown that the unique features of this new dogwood cultivar are stable and reproduced true-to-type in successive vegetative generations.

BRIEF DESCRIPTION OF THE DRAWINGS

FIG. 1. Photograph of 'Pam's Mountain Bouquet'. Colors in the photograph may differ from actual colors due to lighting and light reflectance.

FIGS. 2A and 2B. Close-up Photographs of 'Pam's Mountain Bouquet' bracts.

FIG. 3. Dendrogram illustrating the relatedness of 'Pam's Mountain Bouquet' to other selected *Cornus kousa* cultivars using 11 microsatellite (SSR; Simple Sequence Repeat) markers. Note: Cultivar Beni Fuji is disclosed in U.S. Plant. Pat. No. 8,676.

2

DETAILED DESCRIPTION OF THE NEW VARIETY

A new and distinct cultivar of flowering dogwood tree cultivar, which has fused bracts is provided. This dogwood tree cultivar is botanically known as *Cornus kousa* and referred to by the following cultivar name: 'Pam's Mountain Bouquet'. This cultivar appears to be resistant to powdery mildew caused by *Erisiphe pulchra* and dogwood anthracnose caused by *Discula destructiva*.

10 This new and distinct dogwood tree cultivar was discovered in a planting of seedlings within a cultivated area in Oak Ridge, Tenn. and arose from seed gifted by Ms. Polly Hill. 'Pam's Mountain Bouquet' is a selection from the original seedlings. The instant cultivar was derived from open-pollinated seeds that were bulked from maternal parents 'Big Apple', 'Snowbird', 'Steeple' and an unnamed tree and the potential paternal parents 'Big Apple', 'Julian', 'Steeple' and another unnamed tree (Auge et al., 2002). Thus, it is not possible to ascertain the exact parentage. The subject dogwood tree cultivar differs from all of the potential parents in 15 that the instant cultivar has fused bracts, whereas none of the potential parent cultivars show the same characteristic.

Asexual reproduction of 'Pam's Mountain Bouquet' by rooting of harvested terminal cuttings and grafting of axillary buds onto seedling rootstocks in Oak Ridge, Tenn. and at a nursery located in Belvidere, Tenn. has shown that the unique features of this new dogwood cultivar are stable and reproduced true-to-type in successive generations.

DETAILED BOTANICAL DESCRIPTION

30 The following observations, measurements and comparisons describe this cultivar grown in Oak Ridge, Tenn. Trees

used for this description were about twenty (20) years old. Plant hardiness is expected to be zones 4-9. The color characteristic descriptions use color references to The Royal Horticultural Society (R.H.S.) Colour Chart (published 2001), except where general terms of ordinary dictionary significance are used. Measurements are provided as an average (with ranges also provided as indicated).

The following Table 1 shows microsatellite (SSR) markers used to perform unweighted pair group with arithmetic mean (UPGMA) cluster analysis of 29 cultivars and lines of *Cornus kousa*. GenBank accession numbers are given along with, locus designations, forward (F) and reverse (R) primer sequences (5'-3' direction), and repeat motif:

Botanical classification: <i>Cornus kousa</i> 'Pam's Mountain Bouquet'.					
Unique features: This tree features heavy flowering and exhibits fused bracts. About 82% of all bracts on the cultivar exhibit some degree of fusion (one side, two sides or three to four sides being fused; see data in Table 3).					
TABLE 3					
Cornus kousa 'Pam's Mountain Bouquet' bract characteristics.					
Year	Not fused	One side fused	Two sides fused	3-4 sides fused	50
2008 (n = 50)	7 (14%)	3 (6%)	12 (24%)	28 (56%)	
2009 (n = 50)	10 (20%)	1 (2%)	4 (8%)	35 (70%)	
2011 (n = 50)	9 (18%)	5 (10%)	9 (18%)	27 (54%)	
Mean	9 (18%)	3 (6%)	8 (16%)	30 (60%)	
All categories of fused bracts=82%.					
Disease susceptibility: None noted. Powdery mildew caused by <i>Erysiphe pulchra</i> and dogwood anthracnose <i>Discula destructiva</i> were not observed. Nearby <i>C. florida</i> (flowering dogwood) trees were heavily infested with powdery mildew, but not dogwood anthracnose.					
Insect damage: None noted.

FIG. 1

FIG. 2B

FIG. 2A

FIG. 3

UNITED STATES PATENT AND TRADEMARK OFFICE
CERTIFICATE OF CORRECTION

PATENT NO. : PP25,575 P3
APPLICATION NO. : 13/506624
DATED : May 26, 2015
INVENTOR(S) : Trigiano et al.

Page 1 of 1

It is certified that error appears in the above-identified patent and that said Letters Patent is hereby corrected as shown below:

In the specification

Column 4.

Line 21, "Characteristics of Pam's Mountain Bouquet" should read
--Characteristics of 'Pam's Mountain Bouquet'--.

Column 8.

Lines 13-14,

"49	Whole shape of bracts	Oblong Elliptical	Obovate Ovate"
should read			
--49	Whole shape of bracts	Oblong Elliptical	Ovate Obovate--.

Lines 17-18,

"50	Shape of bract apex	Acuminate Acute	Acuminate Acuminate"
should read			
--50	Shape of bract apex	Acuminate Acute	Acuminate Acuminate--.

Signed and Sealed this
Thirteenth Day of October, 2015

Michelle K. Lee
Director of the United States Patent and Trademark Office
